T. AOKI

LIFE PRESERVER

Filed July 9, 1921

Inventor
T. Aoki,
By Marks Clark
Atty's.

UNITED STATES PATENT OFFICE.

TOKUJIRO AOKI, OF TOKYO-FU, JAPAN.

LIFE PRESERVER.

Application filed July 9, 1921. Serial No. 483,639.

To all whom it may concern:

Be it known that I, TOKUJIRO AOKI, a subject of the Emperor of Japan, residing at Tokyo-fu, Japan, have invented new and 5 useful Improvements in Life Preservers, of which the following is a specification.

The object of this invention is to provide a chair of basket work, to be used in ordinary times as a seat on board ship, and in 10 case of shipwreck, to serve as a floating frame work on the sea to enclose a waterproof canvas sack holding a person, the interior of said sack communicating with the open air by means of a ventilating tube to 15 which is attached a signal flag for calling rescue.

In the accompanying drawings;

Figure 1 is a sectional view of the apparatus in position to receive a person.
20 Figure 2 is a sectional view of the apparatus when used as a chair.
Figure 3 is a side view partly in section of the ventilating tube.
Figure 4 is a plan view of the seat plank 25 to be used as a reporter in time of disaster.
Figure 5 is a sectional view of the same.
Figure 6 is a side view partly in section of the plank drifting on the sea as a reporter.
30 To describe the construction of the apparatus more in detail.

In Fig. 1, (1) is the chair of basket work, (2) buoyant belt engirdling the chair, (3) wooden posts, (4) waterproof canvas sack 35 to hold a person therein, (12) cords to fasten the opening when holding a person, (6) circular glass-paned peep hole, (7) metal fittings for tying the sack to the chair, (13) hoop of the sack to which are fixed the 40 metal fittings (7), (8) a rigid ventilating tube, guided vertically by a track 8^a extending along the back of the chair (9) signal flag, (5) tube formed excretion bag opening at both ends, one end of which hangs outside 45 of the sack while the other is extending deeply into the sack, provided with fastening strings (14 14'), at two points, upper and lower.

In Fig. 2, the canvas sack (4) is shown 50 folded and stored in the chamber under the seat plank (10) which is to serve as a drifting reporter in time of disaster. (11) is a spring peg to sustain the sack on the wooden post.

55 In Fig. 3, the ventilating tube (8) is

shown in detail. (15) is escape pipe, (16) suction pipe, and (17) suction hole.

In Figs. 4 and 5 is shown the plank (10) which serves as a seat in ordinary times and as a drifting reporter in time of disaster. 60 In the centre of the plank is a hole (18), and a cylindrical sack (19) made of waterproof material having a hole (20) in it. On the under surface of the plank is arranged a signal flag (21) attached to a rod. 65

In Fig. 6, is shown the report plank drifting on the water. The cylindrical sack (19) is filled with water flowing in at the hole (20), and hangs down, turning over the plank and standing the signal flag upright 70 on the surface of the water, so that the same may be observed.

To describe the manner of carrying this apparatus into practical use. The canvas sack is stored with provisions, first aid medicines, pocket lamps, etc., and laid away in the chamber under the seat plank, on which a cushion is spread as a seat in ordinary times. In case of disaster, the plank, on which the ship's name and other reports may be registered, is thrown to drift on the sea as a reporter. 75 The person to be saved gets into the sack; the opening is tied up with the draw-strings 12 substantially water tight; the hoop (13) of the sack (14) is lifted up 80 and the metal fittings (7) are fixed to the lock holes in posts 3; and the signal flag is raised, at the same time, to call rescue. This flag is connected to the tube 8 which has its lower end fixed to the hoop 13, so 85 that the tube rises with the hoop.

Thus the sack being provided with provisions etc., and being also waterproof, its inmate is kept free of hunger and wet or cold for a considerable time. Concerning 90 the ventilating tube (8), the suction hole (17) being situated on a little higher level than the escape hole (15), water never rises in the suction hole without closing the escape hole at the same time; the air inside being in that case closed up, water can never get into the sack. When waste substances are to be discharged out of the sack, the tube formed excretion bag is used; the string (14') is unfastened and the discharges are put into the pipe and the string (14') is again fastened; then the string (14) is untied and the discharges are squeezed out of the bag into the sea, the occupant taking care never to fail to tie up the open- 100 105 110

ing immediately. For signalling to call rescue at night, pocket lamps are resorted to; intermittent lights of lamps can be made to shine out through the two peep holes.

6 The stability of the sack is insured as the body of the person rests on the lower part of the sack. The sack is not liable to damage, as it is protected by the frame of basket work. The plank 10 when used as a seat, 10 has the side with a signal flag turned down, so that no inconvenience is felt in occupying said seat while, in case of disaster, it serves quite well as a drifting reporter as described above.

15 Thus it will be seen that the present apparatus may rightly be described as an ideal life preserver, serving both in ordinary times as well as in time of emergency.

Having thus described my invention, 20 what I claim as new, and desire to secure by Letters Patent, is—

1. A life preserver comprising a chair provided with a seat, the portion of the chair arranged beneath the seat forming a 25 chamber, a water-proof sack normally occupying said chamber and capable of being opened out to permit a person to occupy the same, a buoyant belt extending around said chair, windows covered with transparent material arranged in said sack, a hoop 30 connected to the sack, means for fixing said hoop to the chair back in order to hold said hoop in raised position, and a ventilating tube fixed to said hoop and adapted to be raised with the same.

2. In a life preserver, a sack constructed to entirely enclose a person, an open ended flexible tube extending through the wall of the sack and having its outer end opening 40 exteriorly of the sack and its inner end portion arranged within the sack, fastening means arranged within the sack and

connected to said tube near its inner end for contracting the tube near the last mentioned end, and other fastening means located within the sack and arranged near the outer end of the tube for contracting said tube near its outer end.

3. A life preserver as claimed in claim 1 in which the chair is provided with vertical 50 posts, and spring clips arranged on said posts and adapted to support the hoop in raised position.

4. A life preserver as claimed in claim 1 in which the ventilating tube is provided with a suction pipe and an escape pipe, the 55 upper end of the suction pipe being situated at a higher plane than the upper end of the escape pipe in order to prevent water from entering said sack.

5. A life preserver including a chair provided with a seat, the portion of the chair beneath said seat forming a storage chamber, buoyant means arranged on the chair for holding the latter in upright position, 60 when the same is in the water, a water-proof sack adapted to be stored in said chamber and to be opened out to receive a person, a ventilating tube for furnishing air to and discharging air from the interior of 70 the sack when the latter is opened out, and means for holding said tube in a fixed plane relatively to said chair.

6. A life-preserver including a buoyant chair provided with a water-proof sack 75 adapted to receive a person, and a separable buoyant seat for said chair provided on one side with a longitudinal flag and on its opposite side with a sack adapted to be filled with water for holding the flag upright.

In testimony whereof I have signed my name to this specification.

TOKUJIRO AOKI.
